MATCH PACKAGE

Joseph Emanuel Altamos, Worth, Ill.

Application June 9, 1943, Serial No. 490,188

1 Claim. (Cl. 206—29)

My invention relates to the disposition of matches to be carried on the person, and has among its objects and advantages the provision of an improved match package having covers which must be closed before the match can be struck on the usual striking surface.

In the accompanying drawing:

Figure 1 is a perspective view of the match package;

Figure 2 is a similar view with one of the covers 10 open;

Figure 3 is an edge view;

Figure 4 is a sectional view along the line 4—4 of Figure 1;

Figure 5 is a sectional view along the line 5—5 of Figure 1;

Figures 6 and 7 respectively illustrate steps in folding the package to shape;

Figure 8 is a plan view of the paper blank from which the package is folded; and

Figure 9 is a plan view of a paper blank insert.

In the embodiment selected for illustration, Figure 8 illustrates a blank of generally rectangular contour cut at 10 inwardly of and at right angles to the two long edges 12 of the blank. The lines of cut 10 are parallel but spaced to provide a bight area 14 when the blank is bent back upon itself along the lines 16, which lines of bend are in continuation of the respective lines of cut 10. The lines of cut 10 sever the blank to provide two covers 18 bendable along lines 20 paralleling the edges 12, with the covers 18 having widths exceeding half the width of the blank. Thus the bight area 14 is integrally connected with body areas 22 extending short distances beyond the outer ends of the covers 18 and formed with tabs 24.

Figure 9 illustrates a small rectangular blank 26 bendable along lines 28 to provide a channel 30. The area 32 of the blank 26 is of the same size and contour as the bight area 14 and is adhesively secured thereto. In forming the match package of Figures 1 and 2, the blank of Figure 8 is bent back upon itself along the lines 16, which also bends the small blank 26 to the channel contour of Figures 1 and 2.

The tabs 24 are bent approximately along lines 34 and placed underneath the covers 18. The two tabs 24 overlap slightly but are spaced for the reception of the match block 36. Thus the tabs

24 coact with the body areas 22 to provide a channel 38 in which the base end of the match block 36 is positioned. The match block is then made secure by passing staples 40 through the tabs 24, the match block and the body areas 22. When so connected, the heads 42 of the match block are housed in the channel 38 and the latter provides supporting walls for the covers 18 in the closed positions of the latter.

Each body area 22 and its cover 18 are provided with the usual striking surface 44. To remove a match from the block 36, it is necessary that one of the covers 18 be opened, as in Figure 2. To strike the match, it is then necessary to close that cover before the striking surface 44 is accessible. Both sides of the match package are identical, with the covers 18 arranged in diagonal relationship when viewed according to Figure 5. Slightly more than half the matches in the block are accessible through opening of each cover. If the package is turned over for striking purposes after removal of a match, the turning of the package closes the open cover so as to maintain a complete enclosure for the matches. In addition to the cover supporting function of the channel 38, this channel serves as a protective enclosure for the match heads.

Without further elaboration, the foregoing will so fully illustrate my invention, that others may, by applying current knowledge, readily adapt the same for use under various conditions of service.

I claim:

In a match package, a match block, an elongated strip folded transversely to embrace said block, said strip having a pair of slits extending inwardly from its opposite longitudinal edges in parallel arrangement medially of the ends of the strip and aligned with bending lines, the ends of the strip having transversely elongated tab portions extending inwardly from the opposed side edges with their inner ends disposed to overlap when folded, said strip having relatively short slits on the bending lines of the tab portions defining a pair of cover portions bendable outwardly with relation to the match block along a line extending longitudinally of the strip between the inner ends of the slits in each side forming portion of the strip.

JOSEPH EMANUEL ALTAMOS.
